UNITED STATES PATENT OFFICE.

MILLIE JEAN CARLSON, OF SOUTH PASADENA, CALIFORNIA.

WASHTUB.

1,209,555.

Specification of Letters Patent. Patented Dec. 19, 1916.

Application filed May 29, 1914. Serial No. 841,853.

To all whom it may concern:

Be it known that I, MILLIE JEAN CARLSON, a citizen of the United States, residing at South Pasadena, in the county of Los Angeles and State of California, have invented new and useful Improvements in Washtubs, of which the following is a specification.

The invention relates to wash tubs, and 10 has for an object to provide a wash tub of the stationary variety and which is preferably adapted for use in washing clothes and other fabrics.

The invention contemplates, among other 15 features, the provision of a wash tub which will be of a clean and sanitary nature so constructed and arranged that it can be easily flushed, means being provided for rubbing the clothes while the same are being 20 washed and cleaned.

The invention further contemplates a wash tub the body of which is preferably formed of an integral piece of material and which is provided with a suitable splash 25 guard for preventing water from splashing out of the tub.

In the further disclosure of the invention reference is to be had to the accompanying drawings, constituting a part of 30 this specification, in which similar characters of reference denote corresponding parts in all the views, and in which:

Figure 1 is a perspective view of my wash tub; Fig. 2 is a vertical sectional view; 35 Fig. 3 is a plan view; Fig. 4 is a fragmentary view looking at the face of the wash board; Fig. 5 is a fragmentary front elevation of the wash tub, showing the means for securing the wash board in position 40 within the tub; and Fig. 6 is a fragmentary vertical sectional view of a modified form of wash tub, showing the wash board integral with the tub body.

Referring more particularly to the views, 45 I disclose a pedestal 10, which can be of any desired shape or design, and which is adapted to support a tub body 11 preferably formed of a single piece of metal or other material such as soap stone or the like, suitable 50 faucets 12 carried by supply pipes 13 being arranged to extend through the rear wall 14 of the tub 11 as shown. The bottom 15 of the tub body is preferably flat and the rear wall 14 is inclined outwardly as shown, the said tub body having a front wall 16, a part 17 of which projects upwardly and

slightly outward from the bottom 15, thus with the lower part of the rear wall forming a well 18 in which the water for washing is adapted to be contained, the said part 17 of the front wall 16 including at its upper end an integral forwardly inclined part 19 and which, with the part 17, constitutes the complete front wall 16 of the tub body, the said part 19 being preferably inclined at an angle of forty-five degrees to the horizontal as shown.

The upper edges of the rear and front walls 14 and 16 as well as the side walls 20 of the tub body 11 terminate in horizontal 70 flanges 21 and of which the flange projecting from the front wall extends inwardly to form a shelf which, in conjunction with the front wall and the general configuration of the tub body, forms a splash guard 22 to 75 prevent water in the well from splashing outwardly from the tub body when the same is in use.

On the inner face of the front wall 16 and more particularly on the inclined part 19 thereof, there is formed a substantially rectangular depression 23 and in which is adapted to repose a wash board 24 having the edges bordering its face lying flush with the edges bordering the depression 23, the 85 said wash board 24 being rigidly secured in position by a series of screws 25 passed transversely through the inclined board 19 of the front wall 16, from the exterior thereof and having their inner ends in threaded 90 engagement with the wash board 24. Thus it will be seen that the wash board can be conveniently removed when necessary so that it can be cleaned or be replaced by a new wash board when the old one is worn out. 95

The wash board 24 is provided on its face with a series of relatively spaced horizontally extending corrugations 26 terminating a distance from the side edges of the wash board and each of the said corrugations are 100 also inclined relatively to the upper and lower edges of the wash board so that they will be of a self-draining nature, thus preventing water from remaining between the corrugations after the wash board has been 105 used, it being readily apparent that by inclining the corrugations as mentioned the water will readily run from between the same and into the well 18.

In Fig. 6 I have disclosed a slightly modified form of my device and in which instance I provide a wash board 27 similar in all re-

spects to the wash board 24 but formed integrally with the board 19 of the front wall 16 of the tub body 11, the said wash board 27 being of substantially the same size, design and construction as the wash board 24 and similar in every respect thereto with the exception that it is formed integrally with the tub body, whereas the wash board 24 is made removable relatively to the tub body.

10 A soap tray 28 is formed with the tub body and arranged to lie between the faucets 12 as shown, thus providing a convenient receptacle for the soap to be used in connection with the clothes when the same are

15 washed in the tub.

From the foregoing description it will be apparent that the wash tub described is of a simple and durable construction; can be readily cleaned and kept in a sanitary condition and presents a structure wherein the

wash board and tub body are as a unit, thus disclosing a structure which will be conveniently adapted for use in washing fabrics and will efficiently accomplish the result for which it is designed and intended.

Having thus described my invention, I claim:

In a device of the class described, a casing having an inclined wall a corrugated surface on said inclined wall, and a pocket formed at the upper end of said inclined wall and in advance of said corrugated surface, said pocket extending inwardly and around said inclined side.

In testimony whereof I affix my signature in presence of two witnesses.

MILLIE JEAN CARLSON.
